(57) **CLAIM**

The ornamental design for a motor vehicle interior, as shown and described.

DESCRIPTION

FIG. 1 is a perspective view of the motor vehicle interior showing our new design; and,

FIG. 2 is a front view thereof.

The dash-dot broken lines depicting symbolic break lines illustrate boundaries of the claim and are not part of the claimed design. The dash-dash broken lines illustrate portions of the motor vehicle interior which form no part of the claimed design. The dash-dash broken line borders surrounding the two small densely lined rectangular apertures that appear directly under the air vents and the larger densely lined rectangular feature above the glove box compartment serve to disclaim the densely lined interiors of the dash-dash borders from the design.
